UNITED STATES PATENT OFFICE.

MAURICE H. BLOCK, OF BROOKLYN, NEW YORK.

AEROPLANE.

Application filed May 24, 1928. Serial No. 280,162.

This invention relates generally to flying machines, and has more particular reference to a novel aeroplane capable of resisting tail slipping or spinning or other dangerous and undesirable flying features.

The invention has for an object the provision of a device of the class mentioned which is of simple durable construction, desirable and efficient in action, and which can 10 be manufactured and sold at a reasonable cost.

The invention proposes the use of opposite and pivoted chute wing portions on the main wings of a flying machine transversely arranged relative to the fuselage, and opposite and pivoted chute wing portions on the four sides of a chute roof structure attached to the machine preferably above the said main wings. These chute wing portions should 20 be arranged for simultaneous movements for assuming positions normally having little head-on resistance, and quickly movable to positions for adding to stabilize the machine preventing a spin or breaking a spin.

As is generally known one of the greatest dangers in modern flying is that of falling into a tail spin especially while taking off or landing. Many attempts have been made to remedy this shortcoming, but have failed in 30 providing a simple structure readily adapted for performing its function. The positioning and operation of the said chute wings constitute the organization used in bringing out the principles of the invention.

For further comprehension of the invention, and of the objects and advantages thereof, reference will be had to the following description and accompanying drawings, and to the appended claims in which the various 40 novel features of the invention are more particularly set forth.

In the accompanying drawing, forming a material part of this disclosure:—

Fig. 1 is a perspective view of an aeroplane 45 constructed according to this invention.

Fig. 2 is a side elevational view thereof.

Fig. 3 is a fragmentary vertical sectional view, taken on the line 3—3 of Fig. 2.

Fig. 4 is a fragmentary vertical sectional 50 view, taken on the line 4—4 of Fig. 3.

Fig. 5 is a perspective detail view of the main wing, per se.

Fig. 6 is a plan view of the roof structure, per se with the chute wing fully extended.

Fig. 7 is a fragmentary vertical sectional 55 view, taken on the line 7—7 of Fig. 6.

Fig. 8 is a fragmentary edge view, as seen looking in the direction of the line 8—8 of Fig. 6.

The reference numeral 10 indicates generally the main wings of a flying machine having a fuselage 11 with a motor driven propeller 12, a landing gear 13, a stabilizer 14, a fin 15, a rudder 16 and elevators 17 arranged and connected for operation as is common on present day machines. A tail skid 18 is normally held in raised position by a spring 19, and may be lowered to operative position upon landing by drawing wire 20 extending within reach of the pilot. The wings 10 are 60 provided with customary ailerons 21.

Chute wing portions 22 are pivotally mounted on the wings 10 on the front and rear edges thereof, and on opposite sides of the fuselage 11, and arranged for assuming normal positions in the plane of the wings 10, 65 and movable downwards out of this plane.

A chute roof 23 is supported by vertical rods 24 above the wing 10, and is of rectangular shape. On the four sides thereof chute wing portions 25 and 26 are attached. The wings 25 are on opposite sides and have straight ends, and the wings 26 are on opposite sides and have inclined ends for forming a hollow 27 when all of the wings are lowered. 70

Extending longitudinally relative to the fuselage 11, and between the rods 24 are walls 28, hinged at their centers as at 29 to the roof 23 and made of two sections arranged for swinging in a plane parallel with the roof 23 as indicated by the dot dash lines 30 in Fig. 6 and in Figs. 7 and 8. Links 31 pivotally connected with the wings 26 have elongated slots 32 at their other ends engaging pins 33 projecting from the edges of the walls 28 for moving the walls 28 to the positions indicated by the dot dash lines 30 when the wings 26 are pivoted downwards to positions indicated by the numerals 34.

A shaft 35 is mounted across the fuselage in reach of the pilot of the machine and is provided with an operating wheel 36 and several drums 37, and with a ratchet wheel 38 held against rotation by a spring pressed pawl 39 having a releasing handle 36. A plurality of flexible members 40 connect the various pivoted chute wing portions with the drums and are arranged for simultaneously lowering the chute wings upon clockwise rotation of the shaft 35 as seen in Fig. 4, and for raising the chute wings upon anticlockwise rotation. 100

In operation of the device, the pilot operates wheel 36 for lowering the chute wings 22, 25 and 26 simultaneously to inclined positions forming hollows or pockets for holding the machine against tail spinning or the like. Simultaneously with the moving of the wings 26, the walls 28 are moved, adding to the head-on resistance and stability of the machine when desired, that is in lowered positions of the chute wings. Wings 22, 25 and 26 are termed "chute" wings since they form a chute or passage, in this case, for air.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In an aeroplane of the class described, main wings, chute wing portions pivoted on the opposite front and rear edges thereof, and on opposite sides of a fuselage connected with the said main wings, a rectangular roof secured above the said main wings, chute wing portions pivoted on the edges thereof, and means for simultaneously moving all of the said chute wings.

2. In an aeroplane of the class described, main wings, chute wing portions pivoted on the edges thereof, and on opposite sides of the fuselage connected with the said main wings, a rectangular roof secured above the said main wings, chute wing portions pivoted on the edges thereof, and means for simultaneously moving all of the said chute wings.

3. In an aeroplane of the class described, main wings, chute wing portions pivoted on the opposite front and rear edges thereof, and on opposite sides of the fuselage connected with the said main wings, a rectangular roof secured above the said main wings by means of vertical rods, and chute wing portions pivoted on the edges thereof, and means for simultaneously moving all of the said chute wings.

4. In an aeroplane of the class described,

main wings, chute wing portions pivoted on the opposite front and rear edges thereof, and on opposite sides of the fuselage connected with the said main wings, a rectangular roof secured above the said main wings, chute wing portions pivoted on the edges thereof, and means for simultaneously moving all of the said chute wings, including flexible members engaged on drums fixed on a common shaft.

55

60

5. In an aeroplane of the class described, main wings, chute wing portions pivoted on the opposite front and rear edges thereof, and on opposite sides of the fuselage connected with the said main wings, a rectangular roof secured above the said main wings, chute wing portions pivoted on the edges thereof, and means for simultaneously moving all of the said chute wings, certain of the second mentioned chute wing portions having inclined ends.

65

70

6. In an aeroplane of the class described, main wings, chute wing portions pivoted on the opposite front and rear edges thereof, and on opposite sides of the fuselage connected with the said main wings, a rectangular roof secured above the said main wings by means of vertical rods, and chute wing portions pivoted on the edges thereof, and means for simultaneously moving all of the said chute wings, and walls being positioned longitudinally relative to the fuselage and between the said rods, and adjacent the said roof.

75

7. In an aeroplane of the class described, main wings, chute wing portions pivoted on the opposite front and rear edges thereof, and on opposite sides of the fuselage connected with the said main wings, a rectangular roof secured above the said main wings by means of vertical rods, and chute wing portions pivoted on the edges thereof, and means for simultaneously moving all of the said chute wings, and walls being positioned longitudinally relative to the fuselage and between the said rods, and adjacent the said roof.

80

85

90

8. In an aeroplane of the class described, main wings, chute wing portions pivoted on the opposite front and rear edges thereof, and on opposite sides of the fuselage connected with the said main wings, a rectangular roof secured above the said main wings by means of vertical rods, and chute wing portions pivoted on the edges thereof, and means for simultaneously moving all of the said chute wings, and walls being positioned longitudinally relative to the fuselage and between the said rods, and adjacent the said roof, and arranged for motion simultaneously with the said chute wings for adding to the head-on resistance of the aeroplane in lowered positions of the chute wings.

95

9. In testimony whereof I have affixed my signature.

MAURICE H. BLOCK.
